U.S. Appl. No. 29/602,318 Blood Pump On Dialysis Graphical User Interface, Poindexter, filed May 1, 2017.

Primary Examiner — Ian F Whitmore

(57) **CLAIM**

The ornamental design for a display screen with a blood pump icon, as shown and described.

DESCRIPTION

FIG. 1 is a front view of a display screen with a blood pump icon according to a first embodiment of the claimed design; FIG. 2 is a front view thereof shown relative to a different broken-line context;

FIG. 3 is a front view thereof shown relative to a different broken-line context;

FIG. 4 is a front view thereof shown relative to a different broken-line context;

FIG. 5 is a front view thereof shown relative to a different broken-line context;

FIG. 6 is a front view thereof shown relative to a different broken-line context;

FIG. 7 is a front view thereof shown relative to a different broken-line context;

FIG. 8 is a front view thereof shown relative to a different broken-line context;

FIG. 9 is a front view thereof shown relative to a different broken-line context;

FIG. 10 is a front view thereof shown relative to a different broken-line context;

FIG. 11 is a front view of a display screen with a blood pump icon according to a second embodiment of the claimed design;

FIG. 12 is a front view of the first embodiment shown relative to a different broken-line context;

FIG. 13 is a front view of the second embodiment shown relative to a different broken-line context;

FIG. 14 is a front view of a display screen with a blood pump icon according to a third embodiment of the claimed design;

FIG. 15 is a front view of a display screen with a blood pump icon according to a fourth embodiment of the claimed design;

FIG. 16 is a front view of the third embodiment shown relative to a different broken-line context;

FIG. 17 is a front view of the fourth embodiment shown relative to a different broken-line context;

(Continued)

FIG. 18 is a front view of the first embodiment shown relative to a different broken-line context; and, FIG. 19 is a front view of the third embodiment shown relative to a different broken-line context. The outermost broken-line rectangle illustrates the perimeter of a display screen. The remaining broken lines illustrates portions of a graphical user interface. The broken lines form no part of the claimed design.
